UNITED STATES PATENT OFFICE.

ALBERT W. HIGHT, OF BALLARD, WASHINGTON, ASSIGNOR TO THE WASHINGTON PULLEY COMPANY.

PULLEY-FASTENING.

SPECIFICATION forming part of Letters Patent No. 738,611, dated September 8, 1903.

Application filed May 15, 1902. Serial No. 107,404. (No model.)

To all whom it may concern:

Be it known that I, ALBERT W. HIGHT, a citizen of the United States, and a resident of Ballard, in the county of King and State 5 of Washington, have invented a new and Improved Pulley-Fastening, of which the following is a full, clear, and exact description.

The purpose of this invention is to provide means for preventing the slipping of split 10 pulleys on their shafts.

The invention is especially applicable to that class of pulleys in which the sections are held by U-bolts or clevises passing through the pulley-sections and encircling the shaft.

15 My invention involves certain improvements in the key for engaging the U-bolt with the shaft.

This specification is an exact description of two examples of my invention, while the 20 claims define the actual scope thereof.

Reference is to be had to the accompanying drawings, forming a part of this specification, in which similar characters of reference indicate corresponding parts in both views.

25 Figure 1 is a sectional view showing the invention applied, and Fig. 2 is a detail view of the key.

Referring to the drawings, b indicates the shaft and a the sections of the split pulley.

30 c indicates the U-bolts, which are passed through the respective sections a and made to embrace the shaft b, as shown. One or both of the U-bolts carry the keys d, which are formed, as best shown in Fig. 2, with 35 curved outer faces d', concaved longitudinally to lie snugly against the inner side of the clevis or U-bolt and having projections d² at the extremities of its inner side, these projections being sharp and adapted to be forced

40 against the shaft by the pressure of the clevis or U-bolt. The inner faces of the keys are curved on a shorter radius than the outer faces, thus making the projections d² sharp and enabling them to take firm hold on the

45 shaft b and to resist the independent movement of the shaft in both directions. Formed on the outer face d' of the key and intermediate the ends thereof is a stud or projection e, which is adapted to be engaged with the

clevis or U-bolt in a manner to be hereinafter 50 more fully explained, so that the key and clevis will act as one part. When the clevis or U-bolt is drawn up tightly into place, the points or projections d² are forced against the shaft and the clevis, and consequently 55 the pulley-sections are prevented from independent movement on the shaft. Owing to the opposite disposition of the projections d², they hold the parts irrespective of the direction in which they tend to turn. 60

In constructing the device the key is placed in a punch or other suitable holding-tool and the U-bolt or clevis is softened by heat. The projection e of the key is then forced into the heat-softened U-bolt, and finally the U-bolt 65 is cooled to shrink it around the projection e, thus securely fastening the two parts together.

Having thus described my invention, I claim as new and desire to secure by Letters 70 Patent—

1. A pulley-fastening, comprising a key having a concave inner side terminating at each end in a sharp projection, said projections being oppositely disposed, the outer side 75 of the key being convexedly and uniformly curved, and a stud or projection rigidly carried on the key and projecting from the said outer side thereof, for the purpose specified.

2. A pulley-fastening, comprising a key 80 having a concave inner side terminating at each end in a sharp projection, said projection being oppositely disposed, the outer side of the key being convexedly and uniformly curved, and a stud or projection rigidly carried on the key and projecting from the said outer side thereof, for the purpose specified, the outer side of the key being grooved longitudinally of the key to provide a seat for a 85 U-shaped bolt used in the pulley. 90

In testimony whereof I have signed my name to this specification in the presence of two subscribing witnesses.

ALBERT W. HIGHT.
